CLAIM

The ornamental design for a cuff with air delivery tube, as shown and described.

DESCRIPTION

FIG. 1 is a perspective view of a cuff and a portion of an air delivery tube according to an embodiment of our design; FIG. 2 is a top view thereof, with the rear view being identical thereto, with the exception of the cut-off portion of the air delivery tube;

FIG. 3 is a front view thereof, with the rear view being a mirror image thereof, with the exception of the cut-off portion of the air delivery tube;

FIG. 4 is a right side view thereof;

FIG. 5 is a left side view thereof; and,

FIG. 6 is a reverse perspective view thereof.

The broken lines represent environmental structure of the cuff and do not form a part of the claimed design.
